UNITED STATES PATENT OFFICE.

HENRY N. BANKS, OF KINGSLAND, TEXAS.

DESIGN FOR A RAILROAD-SPIKE.

SPECIFICATION forming part of Design No. 27,624, dated September 7, 1897.

Application filed June 30, 1897. Serial No. 643,033. Term of patent 14 years.

To all whom it may concern:

Be it known that I, HENRY N. BANKS, a citizen of the United States, residing at Kingsland, in the county of Llano and State of Texas, have invented and produced a new and original Design for Barbed Railroad-Spikes; and I do hereby declare the following to be a full, clear, and exact description of the same, reference being had to the accompanying drawings, forming a part thereof.

My invention relates to a design for a barbed railroad-spike, and is illustrated in the accompanying drawings, in which—

Figure 1 is a perspective view of a railroad-spike embodying my design. Fig. 2 is a front elevation of the same. Fig. 3 is a side elevation, and Fig. 4 is an opposite side elevation.

The leading features of my design appear in the following description.

1. 1 represents the body of the spike, which is rectangular in cross-section, as shown, and the two sides 2 2 being straight and parallel with each other and smooth-surfaced for their entire length, while the back portion 3 forms a true plane from the head 4 to the point 5, and the front face 6 is parallel with the back portion for its entire length, except as it nears the point, thence diagonally to the point 5, forming the beveled face 7.

2. The head 4 is formed with a flange 8, which extends over the front face 6, the inner or

under face 9 of the head forming an obtuse angle of about fifty-five degrees with the face 6 of the body of the spike. The head 4 is also formed with a flat diagonal face 9' on its upper and rear side, as shown.

3. 10 represent a parallel series of V-shaped diagonal grooves formed in each of the parallel sides 2 2, decreasing in depth from their front edges to about two-thirds of the width, 40 as shown, and said grooves on the one side are beveled oppositely to the corresponding grooves on the opposite side.

4. The upper wall 12 of each of the grooves 10 is inclined with reference to the side in 45 which it is formed, while the opposite wall 13 is formed at a right angle to the side and projects beyond the plane of the side for its entire length to form a spur or barb, as shown.

5. Having thus fully described my invention, 50 what I claim as new and useful, and desire to secure by Letters Patent of the United States, is—

6. The design for a railroad-spike herein shown and described. 55

7. In testimony whereof I affix my signature in presence of two witnesses.

HENRY N. BANKS.
